UNITED STATES PATENT OFFICE.

FRED M. DAVIS, OF CHICAGO, ILLINOIS, ASSIGNEE, BY DIRECT AND MESNE ASSIGNMENTS, OF ONE-THIRD TO PULLMAN COUCH COMPANY, OF CHICAGO, ILLINOIS, A CORPORATION OF ILLINOIS, ONE-THIRD TO GOLD FURNITURE COMPANY, A CORPORATION OF ILLINOIS, AND ONE-THIRD TO KROEHLER MANUFACTURING COMPANY, A CORPORATION OF ILLINOIS.

SOFA-BED.

1,268,099.

Specification of Letters Patent.

Patented June 4, 1918.

Application filed February 18, 1915. Serial No. 9,036.

To all whom it may concern:

Be it known that I, FRED M. DAVIS, a citizen of the United States of America, and a resident of Chicago, in the county of Cook 5 and State of Illinois, have invented certain new and useful Improvements in Sofa-Beds, of which the following is a specification.

This invention relates to convertible furniture of the general type in which a foldable bed bottom is carried directly by a sofa frame in coactive relation with a movable seat member.

The main objects of this invention are to provide an improved form of sofa bed comprising a main section and a plurality of short sections, in which the main section shall be carried demountably by means substantially unitary and integral therewith held pivotally on the sofa frame; to provide improved automatic means for swinging the seat from its sofa position to a position in front of the sofa frame and beneath the bed bottom when the device is unfolded; to provide an improved form of seat carrying frame in which the seat may be tilted in its sofa position for giving access to a storage receptacle thereunder; to provide improved means for supporting the inner end of the head section whereby a longer head section 20 extending substantially to the frame back when unfolded may be used and the middle section correspondingly shortened; to provide a sofa bed having a reduced depth of frame from front to back for a given length 25 of bed bottom; and to provide an improved construction and arrangement of mounting and operating means for the sofa back. Further objects are to provide improved means for controlling the movable front 30 panel of the frame; to provide an improved unitary mounting for the frame pivots adapted for ready interchangeability; and to provide an improved automatic catch for supporting one of the bed sections.

An illustrative embodiment of this invention is shown in the accompanying drawings, in which—

Figure 1 is a fragmentary plan view of the sofa bed in its unfolded position and with part of the sofa frame in section on the line K—K of Fig. 3.

Figure 2 is a side view of said device in its sofa form with the near end of the frame removed.

Fig. 2 is a side view of said device in its sofa form with the near end of the frame removed.

Fig. 3 is a side view of said device in its bed form with the near end removed.

Fig. 4 is an outward view of one of the demountable plates in position.

Fig. 5 is a section on line A—A of Fig. 4.

Fig. 6 is a section on the line B—B of Fig. 2.

Fig. 7 is a section on the line C—C of Fig. 2.

Fig. 8 is a fragmentary front view of the sofa frame and swinging panel showing an automatic closing means.

Fig. 9 is a front elevation of a stop fastening for the sofa back.

Fig. 10 is a plan of the fastening of Fig. 9.

Fig. 11 is a side view of the head section with one corner broken away on the line D—D of Fig. 1.

Fig. 12 is a section on the line E—E of Fig. 3.

Fig. 13 is a fragmentary view showing the middle section and the joints therefor.

Fig. 14 shows a section of the head bearing on the line F—F of Fig. 11.

Fig. 15 is a side view of a modified form of sofa bed in its bed position; parts thereof also being shown by dotted lines in their sofa position.

Fig. 16 is a vertical section of the front part of the seat of Fig. 15 in its sofa position.

In the construction shown in Fig. 1, the sofa bed comprises a frame 1 having ends 2, a back 3, a bottom 4, a top 5, a front 6 and a storage receptacle of box-like construction 7 carried centrally in the lower front part of the frame, said parts preferably being detachable so as to provide a knock-down construction, as will be understood. The foldable bed bottom is in three parts and comprises a long or major section 8 at the foot, a somewhat shorter head section 9 and a much shorter medial section 12.

The foot section 8 at its rear end is provided on each side with a leg or bracket 13 which in its bed position is inclined rearwardly and downwardly, the lower ends being carried by stationary pivots 14 secured

to the frame 1 in its lower forward part. Each leg 13 is unitary with said section and substantially integral therewith. A handle 15 is provided on the free end of section 8.

- 5 The head section 9 is provided with a pair of bearings 16, one on each side medially of its ends, in this instance being somewhat nearer the inner or free end 17 than to the adjacent joint 18. A roller 20 is provided 10 for each bearing and these coact with guides 23 fixed to the ends 2 respectively. Said guides are formed and disposed to cause the head section to move rearwardly in folding, and to bear against the back 3. Said guides 15 also control the elevation of said section and support the same both in bed and storage positions. Each guide 23 has a stop part 25 at its front end and inclines upward and backward nearly to the back 3 and then turns 20 downward abruptly and terminates in a stop part 26. The free end of the bed section is provided with one or more rollers 27 mounted on the lower corner so as to permit of free vertical travel upon the back 3 in folding 25 and unfolding the bed.

The bed bottom joints 18 and 28 are formed to turn in the same direction and to act as stops or rule-joints to arrest turning when the sections are straightened into alignment. Joint 18 is formed to arrest the folding of sections 9 and 12 at right angles. A stop member 18' limits the folding at this point.

In order to support the rear end of the 35 middle section 12 in bed position, automatic locks are provided one for each side, each comprising a yielding member 30 secured to the end 2 adjacent to joint 18.

Each member 30 comprises an upwardly 40 facing shoulder 32 normally held yieldably in the path of a coacting shoulder 33 on said section. The supporting part 34 for shoulder 32 is inclined inward yieldably so as to be pushed outward by the upward movement of the bed bottom, and the upper part 45 of its rear edge is inclined or rounded. The shoulder 32 springs back under the bed shoulder 33 as soon as the middle section reaches its horizontal position. When the 50 foot section is raised for folding the bed, projecting bed shoulder 33 is pushed rearward off from the shoulder 32, thus permitting the middle section to swing downward past the automatic stop 30.

55 The seat device is made to comprise a supporting member 36 and a seat proper 37 mounted tiltably thereon, in order that the storage receptacle 7 may be accessible when the device is in its sofa form, said supporting member being held at all times in substantially horizontal position, as will be explained. Said supporting member comprises a pair of ends 38 preferably connected rigidly by front and back members 39 and 60 40, thus making a rigid rectangular support.

In order that said support may be swung forwardly and downwardly so as to carry the seat in front of the sofa frame and beneath the foot section when the bed is unfolded, two pairs of links 41 and 42 are 70 provided, one pair for each end of the seat support. One link of each pair is disposed in front of the other in substantially parallel relation thereto, said links being all of substantially the same effective length. The 75 swinging ends of said links are pivoted to the ends 38 and the lower ends are mounted turnably in the lower forward part of the sofa frame. The swinging pivots are on the rear part of the seat support. The spacing 80 of the pivots at both ends of both pairs of links is substantially the same. By this arrangement said links and coacting members always operate in effect as a parallelogram, whereby the seat is maintained substantially 85 horizontal. Said links in their sofa position incline backward from their fixed pivots and support the seat, and in their sofa position they incline downward and permit the seat to rest upon the floor. Said links are somewhat angular so as to reach down over the frame panel 6 in their bed position. Normally the seat device rests on said links and bears rearward against the bed section 8.

In order that the seat may be swung automatically by movement of the foot section, connecting means 44 are provided comprising a pair of links opposite ends of which are connected to the seat device and foot section, or to parts of the supporting means 100 therefor respectively.

Means for securing the seat proper turnably on its supporting frame are provided comprising a pair of links 45 one at each end of the seat, each link being pivoted at 105 its forward end to the supporting frame, and at its rear end to the seat adjacent to its lower rear edge, as will be understood. When the front edge of the seat is raised, the links cause the rear of the seat to slide 110 forwardly on the inward flanges 47 of the supporting frame. Roller bearings 49 are preferably mounted on said seat for riding upon said flanges.

A movable panel 50 is provided for the 115 front of the sofa frame beneath the seat, said panel being hinged at its lower edge adjacent to the top of the stationary panel 6 so as to swing forward and thus provide clearance for the swinging of the seat and its supporting links. Means are provided for yieldingly opposing the opening of said panel, and for automatically restoring the same as the sofa bed is folded. Said panel is forced open by contact therewith of the 120 moving links and seat support in unfolding the bed. Said restoring means comprises a spring 53 preferably in the form of a helix having one end secured to the sofa frame and the other to the movable panel. Nor- 130

mainly the front part of the seat may bear upon said panel 50.

In order to facilitate mounting and demounting the seat and bed bottom with respect to the sofa frame, the pivots 14, 56 and 57 for each side are secured to a common mounting or plate 59. The rear legs 13 of the foot section are somewhat resilient and may be sprung upon and off from their 10 pivots 15, but the seat links preferably are secured permanently upon their pivots 56 and 57, as by cotter pins 62. Said plate 59 is rendered readily demountable with respect to frame 1 by providing therein a plurality of slots 64 and 65 formed and arranged to permit of sliding said plate edge-wise into position upon corresponding screws 66 set in the frame ends 2. In order that the screw heads may be flush with the 20 surface of the plate and so give free play for the links, said screws are preferably flat headed and the slots correspondingly beveled to receive the heads. One of said slots 64 opens into an aperture sufficient to receive the head and the others, 65, open on the plate edge.

Automatic locking means are provided to secure said plates when in place. For this purpose a spring member 68 is fastened to the end 2 adjacent to the plate, one end of said spring being secured rigidly and the free end being formed with a shoulder 69 to engage the adjacent edge of the plate 59 to secure the latter against retraction when it has been slid past said shoulder into engagement with its mounting screws. The end 2 is apertured at 70 under the free end of spring 68, so as to permit of pressing the latter inward manually for releasing plate 40 59 when it is desired to remove the seat.

The sofa back 73 is mounted pivotally adjacent to its upper edge, and is swingable. It has a rearwardly disposed top flange 74 normally inclined and adapted to abut 45 against the front edge of the frame top 5 to which it is hinged at 78. Said back lies normally against or adjacent to the upright bed section 8 but may be raised so as to permit of swinging said section forward to its bed 50 position. An automatic lock is provided for securing the back in its raised position, preferably upright, or nearly so, over the top 5. For this purpose a rod 80 is pivoted to the back preferably by means of a bracket 82 55 fixed on the rear of the back, and a stop 83 is secured to one of the frame ends 2, said stop having a vertical aperture for said rod, a shoulder 85 to coact upwardly with a downward shoulder 86 on said rod. Yielding means as a spring 87 urge said rod into locking engagement with said bracket when the back is raised. Means 89 may be actuated manually to release said rod. In bed 60 position the back, if so desired, may be swung down and back against the frame.

part 3, where it will be held by an automatic fastening 90 until manually released for restoring to sofa position. The back when elevated inclines forward somewhat so that its center of gravity is just back of the hinge 78, 70 and the bracket 82 projects forward over said hinge so that the rod 80 will hold the back rigidly.

Stop means 92 are provided on each end 2 against which the free end of the foot section bears in its sofa position, the opposite end of said section being positioned to rest on the floor part 4.

Folding legs 94 are pivoted to the free ends of bed section 8. Automatic control 80 links 95 connect said legs each with a rearward member having movable relation with respect to said section.

In both unfolding and folding, the head section is supported partly by the rigid stop 85 construction of the joints 18 and 29, whereby the unfolding of the middle section with respect to the foot section is limited to 180°, and whereby the folding action of the head section with respect to the middle section is 90 limited to approximately 90°. Ordinarily the bedding is placed on the bed bottom in made-up form before folding, where it may be secured by any desired means as will be understood. When the bed is in its folded 95 form the normal equipment of bedding substantially fills the storage space between the sections and tends to urge the sections apart.

The operation for converting said device from sofa to bed form is as follows: The 100 back is first raised to the position shown in Fig. 3, where it is held temporarily by the lock 80. The bed bottom is then unfolded by grasping the foot rail, or the handle 15, and swinging the same forward to its horizontal position, whereby the seat is lifted from its sofa position and swung forward and downwardly in front of the frame beneath the foot section, and the other sections are swung to their bed position. The head 105 section in so swinging is controlled by the lateral guides 23. The rule joint 28 causes the middle section to lift above and engage the shoulder of the automatic lock 30, and the guides 23 support the head sections. The 110 raised back is then released by pressing inward on the plunger 89 and is swung downward and back into the frame where it is held by the automatic catch 90.

The operation for converting the device 120 from bed to sofa form is as follows: The back is released from its retracted bed position and swung to its upward position where it is held automatically. The bed bottom is then folded and the seat restored to its normal position by grasping the foot of section 8 and swinging it back to its upright position, by which operation the head and middle sections are swung downward and backward to their storage position, the middle 125 130

section being pushed backward and released from the stop 30, and the head section being guided by the rollers 20 and 27 running on members 23 and 3.

5 If the device is to be knocked down for shipment the seat and bed bottom are removed by releasing the pivot plates 59 and then lifting the whole seat and bed mechanism out of the frame 1, there being no 10 other fastenings to release. Then the frame itself may be taken apart in a manner well understood in the art. The device may be assembled by a simple reverse operation.

In the modified construction shown in Fig. 15 the back 100 is carried by the foot section 101 in both its sofa and bed positions. The said back is attached to said section preferably in yielding manner so as to augment the cushion effect and resiliency of the up- 20 holstered back in its sofa position. With this end in view, the upper edge of the back is pivoted at 102 to the outer end of the foot section, and the lower part of the back is attached to the adjacent part of the foot section 25 by yielding means 105, as for instance a flexible strap adapted to limit the divergent swinging of the back with respect to the foot section, yielding compression means 106 being provided, as for instance, coiled 30 springs disposed between the back and the side rails of the foot section. The handle 107 at the top of the back facilitates operation.

In this instance the rearward end of the 35 middle section 109 is guided in lowering and raising by inclined means 112 on the ends of the sofa frame, said guide means having a flat top part 114 on which coacting support means 115 carried by the middle section 40 may rest when said section is raised, said coacting means preferably including a roller bearing 118 arranged to ride upon said guide means.

The guide means on each side for the 45 inner end of the head section 120 each comprises a slotted member 121 which may be disposed substantially horizontally and is preferably open-ended at its rear end 122 to receive the section supporting member 123 50 and to facilitate dismounting the head section when the frame back 3 is removed. In order to definitely insure downward breaking of the joint in folding, yielding means 125 are provided for urging the inner end 55 of the head section upward which device acts on the head section with leverage effect to throw the hinged end downward as the rollers 123 move in their guides 121.

In this modification each controlling link 60 95 for the leg 94 is connected to the middle section 109 instead of to a seat control link, and each seat actuating link 128 is connected to an inner leg 130 of the foot section.

In this form the front panel 132 is uni- 65 tary and extends from the seat to the lower

edge of the sofa frame in its sofa position. It is hinged at its upper edge to the lower front part of the seat member 134. Yielding means 135 urge said panel upward against the underside of the seat when the latter is swung forward to its bed position. Said panel is restored automatically to its vertical position by contact with the links 137 and adjacent sofa frame parts when the seat is swung to its sofa position. Said 75 links in this form may be substantially straight.

The section joints 138 and 139 in this instance may be formed to permit free turning subject only to the support and bed bottom guide means 112 and 121.

The closure panel 5 of this embodiment is provided with a forwardly disposed supplementary swinging part or folding lid 141 of latch-like character formed to receive and 80 overlap the upper end of the foot section 101 when the device is folded. In order that the lid 141 may lift automatically so as to receive the section 101 without any attention from the operator, the front edge is 85 beveled on its lower corner; and in order that said lid may also serve to lock the bed bottom and back in their sofa position, a downwardly projecting lip or shoulder is provided on the beveled edge adapted to engage the upper part of the foot section and prevent forward swinging thereof until the lid 141 has been raised. This feature of 90 automatic control of a top closure lid is not claimed herein, but is set forth and claimed 95 in my copending application, Serial No. 25,477, filed May 3, 1915.

The operation of said modified form is as follows: The top of the back or handle 107 thereon is grasped and swung forward and 100 downward, whereby the foot section is swung directly to its bed position, and the various other members of the device are moved automatically to their corresponding 105 positions. Conversion to the sofa form is accomplished by lifting the free end of the foot section and swinging the same back to its sofa position, all other parts being restored automatically thereby.

By the constructions stated a full length 115 bed bottom may be mounted in a sofa frame of less depth from front to back and of less back height than the depth and height of frames for sofa beds of their type heretofore known. When unfolded there is practically 120 no waste space between the head rail and the frame back, and when folded there is no more space between the head and foot sections than is necessary for the usual bedding. Conversion either way may be effected with ease and without the use of operating springs, especially in the preferred 125 form.

Although but two specific embodiments of this invention are herein shown, it is to be 130

understood that no attempt has been made to show all of the forms which might be used to advantage, and it will be further understood that some of the details of the 5 constructions shown may be altered or omitted without departing from the spirit of this invention, as defined by the following claims.

I claim:

10. 1. In a device of the class described, a frame in combination with a foldable bed bottom comprising a section having legs rigidly fixed thereto adjacent to its rear corners respectively (as disposed in bed position), said legs at their lower ends being mounted turnably on said frame, a seat swingable downwardly in front of said frame and having a pair of supporting links pivoted to each side, said links each having a 15 stationary pivotal support in the lower part of said frame, connecting link means arranged for swinging the seat with said section, said means having substantially direct pivotal relation to said seat and said section 20 respectively and a plurality of rearward sections arranged to fold and unfold automatically.

2. A sofa bed comprising a mounting, in combination with a bed bottom member normally disposed uprightly in the back of said mounting, legs fixed at their upper ends to the lower or rear part of said member and having their opposite ends carried turnably on the lower front part of said mounting, a 25 seat device disposed normally opposite the middle part of said member, supporting links for said seat device at each end where they, together with said seat device and mounting, constitute in effect substantially a parallelogram, a link connecting said seat device and bottom member and having substantially direct pivotal connection thereto respectively, the pivotal ends being disposed approximately one over the other in reverse 30 relation in sofa and bed positions respectively, and a sofa back disposed normally in front of and adjacent to the upper part of said bottom member.

3. A sofa bed comprising a mounting, in combination with a bed bottom member normally disposed uprightly in the back of said mounting, legs fixed at their upper ends to the lower or rear part of said member and having their opposite ends carried turnably 35 on the lower front part of said mounting, a seat device disposed normally opposite the middle part of said member, said seat device comprising a seat proper and a support on which said seat is tiltably mounted, links 40 connecting said mounting and support and arranged to swing said seat device in a substantially ever level position to and from its bed position in front of said mounting and beneath said bottom member.

4. A sofa bed comprising a frame, a fold-

able bed bottom including a foot section having a rigid support mounted swingably in the lower front part of said frame, a head section and a connecting section, said foot and connecting sections having a rule joint 70 connection, and the head section having a joint formed with a stop to limit its folding to substantially ninety degrees, an automatic yielding stop and release support for the connecting section and a guide fixed on 75 said frame for the head section which co-acts therewith.

5. In a device of the class described, a tiltable seat in combination with a swingably mounted support frame accessory to 80 and correspondingly formed to fit under said seat, said frame including end bars and connecting bars at the front and back, and links each pivoted at its front end to one of said end bars and at its rear part of said seat, the latter being held normally in said frame which is formed to fit thereon.

6. In a device of the class described, a tiltable seat in combination with a swingably mounted support frame, said frame including end bars and connecting bars at the front and back, links each pivoted at its front end to one of said end bars and at its rear end to the rear part of said seat, said 95 end bars having inwardly turned flanges on which the seat rests, and said seat having roller bearings at its lower rear corner for riding on said flanges in tilting the seat.

7. A sofa bed comprising a seat and a 100 sofa frame having a panel mounted pivotally at its lower edge beneath the front of said seat, links pivoted to the seat and to the forward part of said frame independently of and spaced back of said panel, said seat being swingable forward and downward in front of said frame, and yielding means co-acting between said panel and frame and urging said panel toward its normal closed position, said panel being swingable forward 105 and downward by the corresponding movement of said seat and links as the latter swing forward and impinge against the back of said panel.

8. A knock-down device, comprising a 115 frame, a mounting plate at each end attachable slidably to said frame by downward movement, co-operatively connected seat and bed members above the mounting plates, and swinging means pivotally connected to said members and to said plates for moving the former to and fro to their sofa and bed positions respectively, said swinging means at each end of the frame comprising separate links for said members, and said plates and 120 frame having coacting shoulder and guide means disposed approximately in upright position, adapted to retain said plates by gravity.

9. In a sofa bed, a sofa frame having back 125

- and side members, and a yieldably mounted front panel, in combination with a foldable bed bottom including an outer section mounted in pivotal relation to said frame, a 5 seat member and supporting means movable forwardly and downwardly to their bed position, operative connecting means for said section and seat member, said panel being hingedly mounted to swing on one of its 10 horizontal edges, and yielding means urging said panel to swing upward, said panel being swingable downward by coaction with said supporting means.
10. A sofa bed comprising a sofa frame 15 having an open front, in combination with a bed bottom operable to open forwardly, a seat movable forwardly and downwardly to its bed position beneath said bed bottom and in front of said frame, links for sup- 20 porting said seat swingably, and a closure panel mounted pivotally on one of its hori- zontal edges, yielding means urging said panel to swing upward, said links being swingable through said open front and said 25 panel being guided by said links in opening and closing.
11. A sofa bed comprising a frame, a fold- able bed bottom including an outer section having supporting means attached rigidly 30 thereto adjacent to its inner end, said sup- porting means being mounted turnably in the lower front part of said frame, a medial section pivoted to said outer section, and a head section pivoted to said medial section, 35 the connection of said outer and medial sec- tions being of rule joint construction and the head and medial sections having a joint

including stop means to limit the folding of said head and medial sections to substantially a right angle, said frame having guide 40 means disposed beside the head section in its bed position, said guide means being formed with its medial part disposed above its ends and above the bed position of the head section, and said head section having 45 means for coacting with said guide means.

12. A main frame having lateral guides, in combination with a foldable sectional bed bottom including an outer section mounted turnably on the front part of said frame, 50 an inner section mounted slidably on said guides, and a connecting section, said guides being formed each with a medial hump and drooping ends, said sections hav- 55 ing limitation swing joints adapted to cause the head section to travel to and fro on said guides in folding and unfolding respectively.

13. In combination, a frame, a back the upper part of which is turnably connected 60 to said frame, a brace turnably connected to said back, a fastening on said frame adapted for securing said brace in a definite position with respect to said frame and back, resilient means adapted for urging said brace later- 65 ally into engagement with said fastening, and yielding means operable manually to disengage said brace from said fastening.

Signed at Chicago this 15th day of February, 1915.

FRED M. DAVIS.
